United States Patent Office

Des. 177,547
Patented Apr. 24, 1956

177,547

AIRPLANE

Lian-Tong Wen, New York, N. Y., assignor of one-third
to Alfred W. Vibber, Ridgewood, N. J.

Application December 7, 1954, Serial No. 33,429

Term of patent 3½ years

(Cl. D71—1)

Fig. 3

Fig. 1 is a plan of an airplane of my design.

Fig. 2 is a front view of the airplane while in flight.

Fig. 3 is a side elevation of the airplane with the retractable landing gear in lowered position.

Fig. 4 is a perspective view of the airplane of Figs. 1, 2 and 3.

The essential features of my design reside in the portions shown in full lines.

I claim:

The ornamental design for an airplane, substantially as shown and described.
